Patented Mar. 6, 1917.

UNITED STATES PATENT OFFICE.

ANDREW J. CALHOUN, OF ROSALIA, WASHINGTON.

BIT.

1,218,053.

Specification of Letters Patent.

Patented Mar. 6, 1917.

Application filed December 27, 1915. Serial No. 68,700.

To all whom it may concern:

Be it known that I, ANDREW J. CALHOUN, a citizen of the United States, residing at Rosalia, in the county of Whitman and State 5 of Washington, have invented new and useful Improvements in Bits, of which the following is a specification.

This invention relates to an improved bit for curbing horses, and has for an object to 10 provide a bit which is humane in action, and also in that it causes no discomfort to the horse when resting idly in its mouth.

Another object of the invention is to provide a bit wherein but relatively slight pressure is necessary to actuate the same to curb 15 the animal, the invention embodying a bit which may normally rest either above or below the horse's tongue, but which, when the reins are drawn taut, always works beneath 20 the tongue and against the gums of the lower jaw.

Another object of the invention is to provide a bit with a laterally extending portion or curve which may normally lie flat in the 25 mouth of the animal either above or beneath the tongue, depending on the will of the animal, but which, when pressure is applied to the bit and the bit has moved into position beneath the tongue, is automatically turned 30 down for engagement between the gums of the lower jaw to work against the same.

Other objects and advantages of this invention will be brought out in the following 35 description of the present preferred embodiment of the invention, the same being shown in the drawing wherein—

Figure 1 is a perspective view of the bit as applied to a horse's mouth showing the bit slackened.

Fig. 2 is a similar view showing the bit when the reins are drawn taut with the laterally extending curved portion turned down and engaging the lower gums.

Fig. 3 is a top plan view of the bit of this 45 invention.

Fig. 4 is an end elevation of the bit, shown in full lines when in operating position, the dotted lines showing the position of the bar when the bit rests idly in the 50 horse's mouth.

Fig. 5 is a plan view of a slightly modified form of bar adapted for use with this improved bit.

The bit comprises a pair of rings 10 carried upon the opposite ends of a bar 11,

which bar is turned over at its ends about the rings 10 to provide connecting eyes 12, as clearly shown in Fig. 3. The intermediate portion of the bar 11 is curved or offset laterally to provide a rounded lateral extension 13 which is curved on a radius sufficiently large to bring the opposite ends of the bar 11 against the inner sides of the gums of the lower jaw. It will be noted that the ends of the bar 11 between the extension 65 13 and the eyes 12 are curved forwardly to provide recesses 14 for the reception of the cheeks of the horse's mouth, and to admit of the turning of the extension 13 backwardly between the gums. 70

In Figs. 1 and 2 the rings 10 are shown as being suspended from the cheek straps 15, while the reins 16 are connected to the rings 10 and extend backwardly therefrom.

When there is no pressure upon the reins, 75 the horse may place his tongue above or below the bit at will, and in Fig. 1, I have shown, for illustrative purposes, the bit as being below the tongue and resting loosely in the mouth of the animal. It is to be understood, 80 however, that the horse, when the reins are slack, may place his tongue below the bit. It will be noted that the bar 11 is supported at the lower portions of the rings 10, this position of the bar holding the projection 13 85 upwardly substantially in parallelism with the lower jaw of the animal, and in the position shown in dotted lines in Fig. 4. The convex or laterally extending portion 13 extends rearwardly toward the back of the 90 horse's mouth.

When pressure is brought to bear on the reins, and the horse's tongue is below the bit, the bit is pressed down in such a manner that the tongue slides out from under it and 95 pressure is brought to bear directly upon the horse's gums. When the reins 16 are drawn taut, the rings 10, as shown in Fig. 2, are drawn backwardly about the cheek straps 15 as a support or pivot point, which action causes the bar 11 to rise to the forward part 100 of the rings 10 and swing into the substantially inclined position shown in full lines in Fig. 4. When in this position the extension 13 is turned down toward the lower part 105 of the jaw substantially in a plane at right-angles with the jaw-bone for engagement between the gums of the lower jaw, and a slight backward pressure on the reins 16 causes the curved extension to wedge or bind 110

between the gums and thus produce the desired effect.

In Fig. 5 of the drawings there is shown a slight modification in the form of the bar 5 11^a, the bar as there shown having an abruptly curved extension 13^a, the arms of which diverge wide apart for wedging engagement between the gums of the lower jaw. The ends of the bar 11^a are straight, as at 10 14^a, and the projection 13^a is given sufficient length or lateral displacement to engage the gums prior to the binding of the ends 14^a against the cheeks of the animal. The bar 11^a is supported upon the rings 10 by the 15 overturned eyes 12^a which are in parallelism with the extension 13^a, as disclosed in the preferred form.

It will be noted that when pressure is not exerted on the reins and the bit lies loosely 20 in the animal's mouth, the horse may place his tongue at will either above or below the bit, but when the reins are drawn taut to check the horse, the bit, should the same be above the tongue, moves the latter backward 25 from beneath the bit, and pressure is brought to bear against the gums. The bit works beneath the tongue at all times when the reins are taut.

I claim:—

30 1. A bit of the character described comprising a bar having a lateral extension arranged to normally lie in parallelism with the mouth of the animal, and rings slidably connected to the ends of the bar and adapted 35 normally to support the bar at their lower portions, said rings being arranged when drawn backwardly by the reins to slide said bar to the forward portions of the rings to turn the bar and project said extension 40 downwardly between the gums of the lower jaw.

45 2. A bit comprising a pair of rings attached to the reins, and a bar free of said reins and slidably mounted on said rings, said bar being curved laterally at its middle portion to provide a wedge-shaped extension arranged to extend rearwardly toward the back of the horse's mouth and adapted for

engagement between the gums of the lower jaw when pressure is exerted upon the reins. 50

3. A bit comprising a bar adapted to be either above or below the animal's tongue when lying loosely in the animal's mouth having a laterally offset portion intermediate its ends presenting diverging arms adapted 55 to wedge in between the gums of the lower jaw, and means for turning said bar to move said bar beneath the animal's tongue and having said offset portion opposite the lower gums and for forcing the offset portion in 60 between the gums.

4. A bit comprising a bar suspended from a pair of rings and adapted to rest loosely in the mouth of the animal above or below the tongue when no pressure on the reins is exerted, eyes upon the ends of the bar slidably mounted on the rings, and a laterally extending portion at the middle portion of said bar lying in the plane of the eyes and projecting toward the central axis of the 70 rings, said bar being adapted to engage beneath the tongue when the reins are drawn taut.

5. A bit comprising a pair of rings adapted to be suspended from cheek straps and attached to the reins, and a bar free of said straps and reins having eyes upon their ends mounted to slide upon the rings, said bar also having a lateral extension intermediate its ends for engagement with the gums of the horse's mouth and having forwardly curved portions at the ends of the bar to provide recesses to accommodate the cheeks of the animal, the said bar being adapted when the reins are drawn taut to slide upon the rings whereby to tilt said extension downwardly against the gums of the lower 85 jaw of the animal. 75

In testimony whereof I have hereunto set my hand in presence of two subscribing witnesses. 90

ANDREW J. CALHOUN.
